CLAIM

The ornamental design for a steering wheel cover, as shown and described.

DESCRIPTION

FIG. 1 is a front perspective view of the steering wheel cover showing my new design;

FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.
The broken lines in the drawings surround portions of the
claims that form the subject of the 1,111,111

steering cover that form no part of the claimed design.

1 Claim, 8 Drawing Sheets
